UNITED STATES PATENT OFFICE

ARMAN E. BECKER, OF NEWARK, AND JACKSON R. SCHONBERG, OF WESTFIELD, NEW JERSEY, ASSIGNEES TO STANDARD OIL DEVELOPMENT COMPANY, A CORPORATION OF DELAWARE

DISTILLATION APPARATUS

Application filed January 9, 1924. Serial No. 685,149.

This invention relates to distillation apparatus, and more particularly distillation apparatus for use with readily decomposable materials. The invention will be fully understood from the following description, taken in connection with the accompanying drawing, in which—

Fig. 1 is a side elevation, with some parts in section, showing one form of embodiment 10 of the invention, all supports and framing being left out for clearness;

Fig. 2 is a side elevation of a modification; and

Fig. 3 is a detail in perspective showing the 15 mounting of a heating element in insulating sections.

Referring to the drawing, the reference character 1 designates a liquid-holding chamber, preferably of generally cylindrical shape, 20 and joining thereon is a vapor-chamber 2, preferably of larger cross-sectional area than the liquid-holding chamber. The vapor-chamber contains a filling of pervious heat-transfer material *h*, for example steel wool, 25 or other metallic wool or in some cases silicate wool, or less desirably coarser filling material, as nipples or rings etc. The filling extends from the grating 3 down to well below the liquid level line. Surrounding the liquid- 30 containing chamber and the vapor chamber are a plurality of coils of resistance-wire heating elements, and around these in turn a jacket affording insulation against external heat-loss. Advantageously the resistance 35 wire may be helical-coil wire of a suitable alloy and the turns about the still are arranged in spaced relation. The wire in each turn constitutes a controllable circuit, for convenience in regulation, and may be wound 40 on mica sheets placed against the still and the turns may be spaced and insulated from each other by asbestos rope or other insulator, and the whole then covered over by a plastic insulation. In our preferred construction, 45 however, the resistance-wires are carried by sectional pieces or blocks 4 of insulation (see Fig. 3), the wire 5 being therein spaced from the still by a very thin wall and having a much thicker wall on the outside serving also 50 as heat insulation for the still. The blocks 4^a

are laid up in courses about the still and the wire is placed in the groove *g*, and each course carries preferably one circuit. When these are in place, the co-operating lagged cover sections or outer sections 4^b are set onto the sections 4^a and the joints may be lightly plastered over, and the blocks as a whole give the effect of an integral jacket of insulation; but if required at any time the sections of any circuit can be dug out for repair or replacement of the resistance wire, without necessitating tearing off the jacket any further, and on replacing the sections the jacket is again complete. These blocks may be made of any suitable insulating composition and can be provided with air-cells if desired for lightness.

The leads from the individual circuit coils are provided with cut-out switches 6, and extend to suitable distributing lines which may carry direct current; but more usually the current available is three-phase alternating current, and for this there may be arranged distributing lines in a three wire set 7, 8, 9 from transformers A, B, C. Ordinary transformers may be used, but we prefer regulable transformers in order to secure additional regulation of current and temperature, and the individual switches 6 can be used chiefly for securing any desired zoning differentials 70 of temperature. As shown in detail in Fig. 2, a desirable construction provides secondary windings in a plurality of coil units 30, switches 31 for connecting coil to coil and switches 32 for connecting the coils to the 75 lines. By this arrangement the secondary coils can be connected up in various combinations; for instance, in series of as many as may be desired, or partly in series and in parallel sets, etc. For example, by closing the 80 switches shown as closed in transformer A of Fig. 2 of the drawing, the coils are connected in series of threes and two sets in parallel. This, of course, is illustrative, and other desired combinations may be had at will. In 85 this manner different rates of current flow may be had in the lines. The primary winding of the transformers is made up in a plurality of units 33. For illustration these coils are shown as connected up by two in series 90. 100.

and three parallel sets. Other combinations may of course be had, as desired. Associated with the primary winding is a resistance 34 in a plurality of elements or sections, each of which is connected to the points 35 of a switch which conveniently may be of dial type. By placing the switch bar across from point 36 to the other points as may be required, no resistance or various sections of the resistance to the extent desired may be connected in, and correspondingly more or less current flow be had. The feed lines 37 may be supplied with three-phase current from a suitable source.

15 Joining on to the vapor chamber 2 is a condenser 13, which is of large cross section to avoid unnecessary resistance to the flow of vapors. A cooling coil of pipe 14 is arranged in the path of the vapors. By flowing water or other desired cooling fluid in regulated amount through the coil the temperature of condensation may be controlled as required. A receiver 15 is joined to the lower part of the condenser and by setting the condenser with 20 a slight downward slope the condensate drains thereto. A further cooling pipe-coil 16 and additional receiver 17 is provided to enable the collection of two separate fractions of condensate, the dam 18 forming a liquid-barrier between the two condenser compartments. If desired, instead of two receivers, one can be provided however where only one fraction of condensate is required. From the receivers a connection 19 leads to a vacuum pump 20.

25 In the form shown in Fig. 2, a furnace F is arranged to heat the liquid-holding chamber 21, or at least the lower portion of it, and electric coils are arranged on successively to 30 the top of the vapor chamber; and joined to the vapor chamber is a condenser 23 which contains a cooling pipe-coil and is provided with a receiver 24. Joining on to the condenser 23 is a further condenser 25 of barometric type and an additional receiver R is connected thereto. From the condenser 25 a connection 27 leads to a vacuum pump 28.

35 In the operation of distilling with our apparatus, the material to be distilled, for example, a lubricating oil stock is introduced through the feed pipe f, and the switches 6 are closed for the circuits which are to be used and the current is turned on. If a fractionating action is desired, only the circuits about the liquid are closed. If no fractionating action is desired, but instead a distillation without reflux, the circuits up about the vapor space are also closed, or at least a sufficient number of them in suitable spacing to secure 40 the temperatures desired at the respective points of measurement. Additional regulation is secured by the switches of the regulable transformers. A cooling fluid is circulated through the cooling pipe-coils in the 45 condenser to maintain the temperature there

at the desired point, and the vacuum pump is operated as required. If some steam is desired in the still, it may be furnished by a pipe 29 which extends near the floor of the still and is perforated to distribute the steam, and the extra condenser may be operated at a temperature to condense out the steam differentially from the oil.

50 The temperature in the still may be measured by thermometers in wells at desired points, but we prefer indicating or recording thermometers, as conventionally shown at T, T¹, T², T³.

55 What we claim is:

1. In an electrical heating installation for oil stills having a liquid chamber and a vapor chamber, the improvement which comprises a number of closely spaced electrical heating elements arranged to supply heat throughout the extent of both said chambers, and means for regulating the flow of current through said elements.

60 2. In an electrical heating installation for cylindrical oil stills having a liquid chamber opening directly into a vapor chamber of larger diameter, the improvement which comprises circumferential resistance elements at closely spaced intervals from top to bottom of both said chambers, and means for regulating the flow of current through said elements.

65 3. In an electrical heating installation for oil stills having a liquid chamber and a vapor chamber, the improvement which comprises a number of closely spaced resistance wires arranged to supply heat throughout the extent of said vapor chamber, and means for regulating the flow of current through said wires.

70 4. In an electrical heating installation for vacuum distillation apparatus, the improvement which comprises a plurality of electrical heating coils in spaced relation about said still, and mounted in sectional blocks of insulating material, said blocks fitting together to form a jacket about the still, and means for regulating the current to the coils.

75 5. In an electrical heating installation for vacuum distillation apparatus, comprising a liquid holding chamber, a vapor chamber of at least as large cross sectional area joining on thereabove and a pervious heat transfer filling in the chamber, the improvement which comprises a plurality of resistance wire heating coils in spaced relation about said liquid holding chamber and vapor chamber, and mounted in sectional blocks of insulating material, said blocks fitting together, lead wires from said heating coils, and cut-out switches in said leads.

80 6. In an electrical heating installation for distillation apparatus, comprising a cylindrical liquid holding chamber, a vapor chamber of larger cross-sectional area joining on thereabove, a pervious heat transfer filling in the

chamber and extending into the liquid holding chamber, the improvement which comprises a plurality of resistance wire heating coils in spaced relation about said liquid holding chamber and vapor chamber, and mounted in sectional blocks of insulating material, said blocks fitting together to form a jacket about the still, lead wires from said heating coil to three-wire distribution lines, cut-out 10 switches in said leads, and a set of regulable transformers for supplying said lines.

7. In an electrical heating installation for distillation apparatus, the improvement which comprises combined electrical and heat 15 insulating elements made up of block sections grooved to receive a heating wire, and lugged outer sections cooperating therewith to cover the wire and provide a jacket for said fluid heating apparatus.

20 8. Means of supporting a plurality of resistance heating wires in spaced relation, consisting of sectional blocks of insulating material fitting together to form a jacket about the body to be heated, said blocks being made 25 up of a grooved section to receive the heating wire and a lugged outer section to cover the heating wire and provide a jacket for the heated body.
